Primary Examiner — Barbara Fox*Assistant Examiner* — Aram Kwon(74) *Attorney, Agent, or Firm* — J. Wiley Horton(57) **CLAIM**

The ornamental design for an “auto stereo mounting device,” as shown and described.

DESCRIPTION

FIG. 1 is a perspective view of an auto stereo mounting device, showing my design;
 FIG. 2 is a front elevation view of FIG. 1;
 FIG. 3 is a rear elevation view of FIG. 1;
 FIG. 4 is a left side elevation view of FIG. 1;
 FIG. 5 is a right side elevation view of FIG. 1;
 FIG. 6 is a top plan view of FIG. 1; and,
 FIG. 7 is a bottom plan view of FIG. 1.

The broken lines shown in all views illustrate mounting features which form no part of the claimed design.
